UNITED STATES PATENT OFFICE.

WILLIAM D. KYLE, OF MILWAUKEE, WISCONSIN.

STRAIN INSULATOR.

Application filed December 30, 1921. Serial No. 525,843.

To all whom it may concern:

Be it known that I, WILLIAM D. KYLE, a citizen of the United States, and resident of Milwaukee, in the county of Milwaukee, 5 and State of Wisconsin, have invented new and useful Improvements in Strain Insulators, of which the following is a description, reference being had to the accompanying drawings, which are a part of this 10 specification.

The invention relates to strain insulators. The object of the invention is to improve upon the usual stiff metal clevis and its connection with the bolt running through the 15 insulator, by providing a flexible cable forming the clevis and firmly anchoring this cable in a simple and effective manner for its connection with the bolt. By this arrangement a standard size clevis may be 20 used for all sizes of strain insulators, whereas it has been necessary, with the stiff metal clevis, to keep different sizes on hand to fit different sizes of insulators.

The invention further consists in the 25 several features hereinafter set forth and more particularly defined by claims at the conclusion hereof.

In the drawings: Fig. 1 is a front elevation view of a device embodying the invention, parts being shown in section; Fig. 2 is a side elevation view thereof; Figs. 3 and 4 are vertical sectional views showing slightly modified constructions.

In the drawings the numeral 4 designates 35 a strain insulator usually made of porcelain and having a hole 5 therein for the guy cable and a groove 6 extending around one end to opposite ends of said hole and an opening 7 extending at right angles to said hole 5 receiving the clevis bolt 8.

According to the present invention the clevis is formed by a flexible metal cable 9 and means for operatively connecting the ends thereof to the bolt 8.

For connecting the ends of the cable 9 with the bolt 8, I preferably provide eyes 10 to which the ends of the cable are secured in each instance by casting the metal forming the eye about the coiled end 11 of the 45 cable. The metal forming the eye is preferably cast iron or lead. Where lead is used hubs 12 may be formed integral with the main portion of the eye and project into the flared ends 13 of the opening 7, as shown 50 in Fig. 3, or the hubs 12' extend into meeting engagement, as shown in Fig. 4. These

eyes are made long enough to form a good bearing connector with the bolt.

With this construction the ends of the cable are securely embedded in the eyes 60 and these eyes are mounted on the bolt on either side of the insulator 4 and drawn into engagement therewith by tightening up the nut 14 of the bolt 8. The cable clevis readily adapts itself to strain insulators of 65 different sizes and by making this cable loop of a size to take the largest size insulator it may be used on all other sizes so that neither the manufacturer nor the user has to keep a stock of clevises of different 70 sizes on hand, as the one standard clevis is suitable for all sizes of insulators.

I desire it to be understood that this invention is not to be limited to any specific form or arrangement of parts except in so 75 far as such limitations are specified in the claims.

What I claim as my invention is:

1. In a strain insulator, the combination 80 with the insulator, and the bolt passing therethrough, of a loop of flexible cable adapted to take insulators of different sizes, and means for securing the ends of the cable to the bolt on opposite sides of said insulator.

2. In a strain insulator, the combination 85 with the insulator, and the bolt passing therethrough, of metal eyes fitting onto the bolt on opposite sides of the insulator, and a loop of flexible cable having its ends secured to said eyes.

3. In a strain insulator, the combination 90 with the insulator, and a bolt passing therethrough, of metal eyes fitting onto the bolt on opposite sides of the insulator, and a cable loop having its ends embedded in said eyes.

4. In a strain insulator, the combination 95 with the insulator, and a bolt passing therethrough, of metal eyes fitting onto the bolt on opposite sides of the insulator, and a cable loop having coiled ends embedded in said eyes.

5. In a strain insulator, the combination 100 with the insulator having a clevis bolt opening with flared ends, and a bolt passing through said opening, of metal eyes fitting onto the bolt and having extensions seated in said flared ends, and a cable loop having its ends secured to said eyes.

In testimony whereof I affix my signature.

WILLIAM D. KYLE.
